DESIGN FOR A SHOE

John Marx Miller, Hagerstown, Md., assignor to
The Hagerstown Shoe & Legging Company,
Hagerstown, Md., a corporation of Maryland

Application June 25, 1934, Serial No. 52,336

Term of patent 3½ years

To all whom it may concern:

Be it known that I, JOHN MARX MILLER, a citizen of the United States, residing at Hagerstown, in the county of Washington and State of Maryland, have invented a new, original, and ornamental Design for a Shoe, of which the following is a specification, reference being had to the accompanying drawing, forming part thereof.

Fig. 1 is a plan view of a shoe, showing my new design; and

Fig. 2 is a side view thereof.

The essential feature of the present invention is an ornamental gore or the like, extending across the kiltie tongue, for holding the tongue snugly in place, the ornamental gore, in cooperation with the kiltie tongue, giving to the shoe a new, neat and ornamental effect.

I claim:

The ornamental design for a shoe, as shown and described.

JOHN MARX MILLER.
